United States Patent Office

Des. 206,880
Patented Feb. 7, 1967

206,880

SHAVER CHARGING STAND

Burton Kelly, Western Springs, Ill., assignor to Sunbeam
Corporation, Chicago, Ill., a corporation of Illinois

Filed July 9, 1965, Ser. No. 86,094

Term of patent 14 years

(Cl. D26—15)

Fig. 1.

Fig. 3.

Fig. 4.

Fig. 5.

FIG. 1 is a front perspective view of a shaver charging stand embodying my new design;

FIG. 2 is an exploded front perspective view of the shaver charging stand of FIG. 1 having the cover removed from the stand;

FIG. 3 is a rear elevational view of the shaver charging stand of FIG. 1;

FIG. 4 is a right side elevational view thereof; and

FIG. 5 is a bottom plan view thereof.

The broken line showing of a representative electric shaver in FIG. 2 is for illustrative purposes only.

I claim:

The ornamental design for a shaver charging stand, as shown and described.
